UNITED STATES PATENT OFFICE.

GEORGE G. TAYLOR, OF CRAFTON, AND ISMOND E. KNAPP, JR., OF CORAOPOLIS,
PENNSYLVANIA.

PROCESS OF PRODUCING AMMONIA AND AMMONIUM COMPOUNDS.

1,315,534.

Specification of Letters Patent.

Patented Sept. 9, 1919.

Application filed September 13, 1917. Serial No. 191,185.

To all whom it may concern:

Be it known that we, GEORGE G. TAYLOR and ISMOND E. KNAPP, Jr., citizens of the United States, and residents of Crafton and 5 Coraopolis, respectively, in the county of Allegheny and State of Pennsylvania, have invented a new and useful Improvement in Processes of Producing Ammonia and Ammonium Compounds; and we do hereby 10 declare the following to be a full, clear, and exact description thereof.

Our invention relates to the manufacture of ammonia or ammonium compounds from the so-called fixation products of the 15 action of carbids with nitrogen gas.

In such production of ammonia or ammonium compounds, great difficulty has been experienced in converting a large percentage of the nitrogen to ammonia by the 20 use of steam.

In order to facilitate this conversion, it has been customary to heat the nitrogen-containing material with steam under pressure, or to mix the material with some substance,—such as sodium carbonate, lime or sodium sulphate,—and then subject this 25 mass to the action of water and steam in an autoclave, or a device for carrying out chemical reactions with the aid of heat and pressure.

In the process herein described, the nitrogen-containing material is not mixed with any other substance, nor is it necessary that the reaction be carried on under pressure 35 equal to or greater than atmospheric pressure, and we are able to obtain approximately 92 to 95 per cent. of the nitrogen in the form of ammonia gas and ammonium compounds. It is one of the advantages of 40 this invention, therefore, that we may carry on our reactions in the production of ammonia at, above or below atmospheric pressure. We have found in practice, however, that for practical considerations it appears 45 best to carry on the reactions at atmospheric pressure.

In our process for the production of ammonia and ammonium compounds, the nitrogen-containing material—such as that obtained from the action of nitrogen gas upon calcium carbide, for example—may be carried out in different ways, without affecting the principle underlying our invention, provided that the material be subjected, at a 55 temperature below 350° C., to the action

of steam or water until a point of approximate or complete saturation is reached. This may take place below 100° C. by subjecting the material either to wet steam or water or it may take place at a temperature 60 above 100° C. by the application of steam or water. The temperature is then raised to or above a temperature of approximately 450° cent.

While in our process a variety of nitrogen 65 compounds may be employed, we have found that the process is particularly adapted for treating such nitrogen compounds as are produced by the combinations of metal, carbon and nitrogen, such as are described in 70 our companion application, Serial No. 190,875, filed on the 12th day of September, 1917. One of the principal substances, therefore, with which the present process is concerned is what we term "dimetal isocyanid," 75 though it is to be understood that our invention is in no way limited to the treatment of this substance, but we may employ not only any of the compounds produced by the process hereinafter briefly referred to, but 80 also any other nitrogen compounds, which are susceptible to reduction by steam.

The products which we prefer to employ—and particularly dimetal isocyanid—may be produced in the following manner:

A metal oxid—such as calcium oxid, for example—is mixed with a suitable proportion of coal and is coked preferably in a by-product oven whereby the ammonia, light oils and other valuable products are recovered, and the gas from which may be used to furnish all or a part of the heat necessary to complete the coking process.

The resulting mixture, consisting of a rigidly cemented mass of metal oxid and coke, is then withdrawn from the furnace, and, if necessary or desirable, crushed by any suitable form of crusher. It is then transferred in whole or in part, or from time to time in such increments as are most suitable, to an electric furnace.

The electric furnace employed in carrying out this process may be of any approved design, but we prefer to employ a furnace which consists of one or more pairs of electrodes supported in such a way as to be easily adjusted, but preferably to form an angle of over 90° with each other, and the ends of these electrodes should be far enough apart so that fragments of the mixture of 110

metal oxid and coke will readily fall between them. A hearth of carbon or other suitable material may be placed below the pair of electrodes to form a barrier whereby the coke mixture is held between the ends of the electrodes, and thereby is exposed to the fullest possible action of the electric current.

The coke mixture prepared as above is then acted upon by the electric current, which is preferably an alternating current with voltage below 100, although we do not limit ourselves to this, and a metal carbid is formed. The carbid so formed immediately flows down between the electrodes and the hearth and collects at a point sufficiently far from the heat zone so that its temperature is relatively low. The carbid so collected may be removed from time to time as necessary or desirable, or it may fall upon a conveyer and be continuously removed.

The carbid once formed does not dissociate into metal and carbon since it is immediately cooled below its dissociation point, and it is sufficiently cooled so that it is not acted upon by the oxygen in the air to form oxide of carbon and metal oxid.

The metal carbid so produced is very pure and free from metal oxid, carbon, and metal, and, therefore, is a far superior product for the purposes hereinafter to be described, inasmuch as the yield of the products is increased and their production facilitated by the use of a carbid of a high degree of purity.

The metal carbid so formed, or a metal carbid made by other processes, is then crushed to a suitable size by a ball mill or other device, and is put into a furnace or retort of such design that the products of combustion, if combustible materials are used for heating, are not allowed to penetrate to the interior of the furnace or retort in such amount as to produce an injurious effect upon the product and thereby cause decomposition of the metal carbid, or of the products subsequently formed.

Before introducing the carbid into the furnace, it may be mixed with a suitable proportion of a catalyst, such as a metal chlorid, fluorid, or a mixture of chlorid and fluorid—such as a mixture of sodium chlorid and calcium fluorid, for example—whereby the combination between the nitrogen and the metal carbid is facilitated and proceeds rapidly at a much lower temperature than would be necessary if the above-mentioned catalyst were absent.

A current of nitrogen gas, which may have been prepared by purifying the products of combustion of the coking retorts above referred to, by the fractional distillation from liquid air, or by other means of preparing nitrogen gas, is caused to pass over and through the mass of carbid.

Whether or not a catalyst is used, a combination between the nitrogen and the carbid is effected very rapidly whenever the temperature is raised to or above a dark red heat, and heat is liberated by the reaction, which serves in part to maintain the reacting mass at the proper temperature.

The above brief outline of the method of preparing the materials, which may be employed in the process forming the subject of this invention, is more fully described in the specification of our companion application above referred to.

The nitrified product so formed contains some lime, a trace of carbid, and one or more compounds containing metal and nitrogen, or metal, carbon, and nitrogen, together with a certain amount of carbon liberated by the reaction, and a small amount of inert matter, mostly from the ash in the coal, and impurities from the metal oxid used. The amount and nature of these compounds may be controlled to a certain extent by the temperature of the furnace and by the rapidity of the reaction, which may be accelerated or otherwise influenced by the addition of a catalyst.

Among the combinations which are thus formed by the action of nitrogen on a carbid, are isocyanid—or, as we term it, “dimetal isocyanid”. There may also be formed nitrid, cyanamid, cyanid and various other compounds containing metal, carbon and nitrogen.

The predominant combination, however, when the temperature is below 1000° cent., is usually the dimetal isocyanid of the formula $M_2N_2C_2$, in which M is a metal, and when conditions are properly regulated, this combination is formed to the practical exclusion of all others.

The nitrid formed is from such small amount of pure metal as may be present in the reacting mass; the other compounds, such as dimetal isocyanid, isocyanid, cyanamid, etc.—are formed by the action of the nitrogen on the carbid.

The mixture from the nitrifying furnace, consisting in whole or in part of the new and valuable compounds, particularly dimetal isocyanid, may be used with special advantage in carrying out the process of the present invention hereinafter described.

In the accompanying drawings are illustrated diagrammatically two forms of apparatus in which our improved process for producing ammonia or ammonium compounds may be carried out. In said drawings, Figure 1 illustrates a simple form of apparatus for carrying out what we term an intermittent process; and Fig. 2 illustrates an apparatus for carrying out what we term a continuous process.

In Fig. 1, 1 indicates a suitable retort in which the nitrified material 2 is to be treat-

ed. Said retort has a steam connection 3 and an outlet for leading to any suitable form of condenser 5 through which the material is conveyed and from which it is conducted by a pipe 6 to a suitable scrubber 7, from which the CO_2 may escape by pipe 8.

In carrying out our improved process, the material is treated with water in the form of liquid or vapor either before or 10 after the material is placed within the retort 1; and heat is gradually applied to the retort in any desired manner. The production of ammonia begins almost immediately, and continues steadily to increase as the 15 temperature of the retort gradually rises, until the material in the retort has reached approximately 500° cent., when a copious evolution of carbon dioxid gas occurs, and the resulting product consists very largely 20 of ammonium carbonate and bicarbonate formed by the reaction between ammonia, water and CO_2 , and such other ammonium compounds as may be formed at the temperatures attained by the mixed gases and 25 vapors during their passage through the retort and through the condenser.

When the reaction is over and the condensate from the retort contains very little or no ammonia, the retort is cooled, cleaned 30 out, and a new charge is placed therein.

Referring now to Fig. 2 of the drawing, which illustrates an apparatus for carrying out our process continuously, 9 indicates a suitable hopper from which the nitrified material may be supplied to a suitable 25 form of conveyer having a steam connection, as at 11. At the end of the conveyer opposite the hopper 9 may be connected a suitable container 12 to receive the residual material 40 after the reaction has taken place and the vapors or gases from the reactions are conveyed by a pipe 13 to a condenser and scrubber, as before described.

In this form of apparatus, the conveyer 45 may be utilized as the retort through which the charge is gradually and continuously fed, and in which it encounters a steady increase in temperature up to the point where the last of the ammonia and ammonium 50 compounds is given off,—whence the residual material falls into the container 12 and may be removed by such device as does not interfere with the continuous operation of the retort. During this heating operation, steam is led through the retort to the 55 conveyer, and together with the ammonia or other products, passes through a condenser and scrubber, as heretofore described.

The condensate consisting of water in 60 which is dissolved ammonia, ammonium carbonate, bicarbonate and other ammonium compounds may be collected as such and the ammonia distilled off and recovered by suitable means, while the water solution of 65 ammonium carbonate, bicarbonate and other

compounds is concentrated and the salts crystallized therefrom; or the solution of ammonium carbonate, bicarbonate, or other ammonium compounds may be treated with a base—as sodium hydrate, for example—70 and thereby decomposed into ammonia gas, which may be distilled off and recovered.

The condensate may also be led into sulfuric acid and the resulting ammonium sulfate recovered by crystallization, or other 75 well-known means; or, the condensate may be led into nitric acid, and the ammonium nitrate recovered therefrom; or, finally, the condensate may be treated in any way that shall seem necessary or advisable. 80

The great purity of the ammonia formed from the nitrogen compounds heretofore more particularly described is of especial value in the production of nitric acid, as the presence of impurities in the ammonia ordinarily causes great difficulty in the operation of the process. 85

The residual material formed as a by-product in the above-described production of ammonia—such as metal oxid, hydroxid, 90 carbonate, and carbon—may be used in various ways,—for example, it may be calcined and mixed with coal, or mixed with coal without calcining, and coked again, being then formed into carbid and again nitrified,—thus rendering the entire process a cyclic one. 95

While we have above described in general outline the steps employed in producing ammonia and ammonium compounds, and 100 have indicated the order in which said steps may be followed and carried out, it is to be understood that the invention is not limited to the precise process described, nor is it in any way limited in respect to the order of 105 steps other than within the scope of the appended claims.

What we claim is:

1. The process of producing ammonia and ammonium compounds, which consists in 110 saturating with water a nitrogen-containing material, and then heating the material decomposable with the formation of ammonia in the presence of heat and moisture to or above 450° cent. in the presence of steam. 115

2. The process of producing ammonia and ammonium compounds, which consists in treating a crude material containing nitrogen and lime with water until the lime is substantially hydrated, and then heating the 120 material to or above 450° cent. in the presence of steam.

3. The process of producing ammonia and ammonium compounds, which consists in 125 saturating with water a crude material containing nitrogen and resulting from the interaction of a carbid and nitrogen, and then heating the material to or above 450° cent. in the presence of steam.

4. The process of producing ammonia and 130

and ammonium compounds, which consists in treating with steam below 350° cent. to the point of substantial saturation a product resulting from heating a carbid in an atmosphere of nitrogen gas while maintaining the heat at a point not in excess of 1000° cent. until the reaction is completed, and then heating the material to or above 450° cent. in the presence of steam at atmospheric pressure.

20. The process of producing ammonia and ammonium compounds, which consists in treating with water to the point of substantial saturation a product resulting from 15 heating calcium carbid in an atmosphere of nitrogen gas while maintaining the heat at a point not in excess of 1000° cent. until the reaction is completed, and then heating the material to or above 450° cent., in the presence of steam at atmospheric pressure.

21. The process of producing ammonia and ammonium compounds, which consists in treating with steam below 350° cent. to the point of substantial saturation a product resulting from heating calcium carbid in 25 an atmosphere of nitrogen gas while maintaining the heat at a point not in excess of 1000° cent. until the reaction is completed, and then heating the material to or above 450° cent. in the presence of steam at atmos- 30 pheric pressure.

In testimony whereof, we the said GEORGE G. TAYLOR and ISMOND E. KNAPP, Jr., have hereunto set our hands.

GEORGE G. TAYLOR.
ISMOND E. KNAPP, Jr.

Witnesses:

JOHN F. WILL,
IRENE F. GEYER.

It is hereby certified that Letters Patent No. 1,315,534, granted September 9, 1919, upon the application of George G. Taylor, of Crafton, and Ismond E. Knapp, of Coraopolis, Pennsylvania, for an improvement in "Processes of Producing Ammonia and Ammonium Compounds," were erroneously issued to said inventors, said Taylor and Knapp, as owners of said invention, whereas said Letters Patent should have been issued to *James Henry Reid, of Pittsburgh, Pennsylvania, as assignee of the entire interest in said invention*, as shown by the record of assignments in this office; and that the said Letters Patent should be read with this correction therein that the same may conform to the record of the case in the Patent Office.

Signed and sealed this 25th day of November, A. D., 1919.

[SEAL.]

M. H. COULSTON,

Acting Commissioner of Patents.
